FINGER RING

Bernard I. Mechanic, 2425 Oakton St.,
Evanston, Ill. 60202

Filed Feb. 17, 1972, Ser. No. 227,343

Term of patent 14 years

Int. Cl. D11—01

U.S. Cl. D45—10 C

FIG. 1 is a top plan view of a finger ring showing my new design;

FIG. 2 is a front elevational view looking in the direction of the arrows 2—2 in FIG. 1;

FIG. 3 is a rear elevational view looking in the direction of the arrows 3—3 in FIG. 1;

FIG. 4 is a side elevational view looking in the direction of the arrows 4—4 in FIG. 2; and

FIG. 5 is a side elevational view thereof looking in the direction of the arrows 5—5 in FIG. 2.

I claim:

The ornamental design for a finger ring, as shown.
